DESIGN FOR A COMBINATION DISPLAY STAND AND DISPENSING CABINET FOR GUMMED TAPE, STRING, AND ELASTIC BANDS

David A. McCowan, Toronto, Ontario, Canada

Application June 10, 1935, Serial No. 57,207
In Canada June 5, 1935

Term of patent 14 years

To all whom it may concern:

Be it known that I, David A. McCowan, a subject of the King of Great Britain, residing at the city of Toronto, in the county of York, Province of Ontario, Canada, have invented a new, original, and ornamental Design for a Combination Display Stand and Dispensing Cabinet for Gummed Tape, String, and Elastic Bands, of which the following is a specification, reference being had to the accompanying drawing, forming part thereof, in which

Fig. 1 is a front perspective view of the article, showing my new design; and

Fig. 2 a rear perspective view thereof.

I claim:—

The ornamental design for a combination display stand and dispensing cabinet for gummed tape, string and elastic bands, as shown.

DAVID A. McCOWAN.
